UNITED STATES PATENT OFFICE.

WILLIAM GRUNOW, JR., OF NEW YORK, N. Y., ASSIGNOR TO JOHN F. ALVORD, OF TORRINGTON, CONNECTICUT, AND WILLIAM B. THOMPSON, OF NEW YORK, N. Y.

IGNITING MECHANISM FOR INTERNAL-COMBUSTION ENGINES.

1,205,194.

Specification of Letters Patent. Patented Nov. 21, 1916.

Application filed October 28, 1915. Serial No. 58,379.

To all whom it may concern:

Be it known that I, WILLIAM GRUNOW, Jr., a citizen of the United States, residing at 401 West One Hundred and Twenty-fourth street, in the city and county of New York and State of New York, have invented certain new and useful Improvements in Igniting Mechanism for Internal-Combustion Engines, of which the following is a specification, reference being had to the accompanying drawing.

This invention relates to electric igniters, as used with internal combustion engines, and comprises a make and break igniter having two electrodes, and operated by the engine piston engaging a plunger connected to or forming one of the electrodes thereby separating contact points on the electrodes, and producing a spark.

An object of the invention is to provide means for advancing and retarding the timing of the spark in relation to the position of the engine piston.

A further object is to assemble the electrodes, the means for restraining the electrodes, and the means for advancing and retarding the breaking of the electrodes in one unit, adapted to be removed and replaced on the engine without disassembling any of the related parts, thereby affording the same simplicity of replacement with this type of igniter as is offered with the usual "spark plug."

While piston operated plugs have been known they have not come into commercial use owing to several practical difficulties eliminated in this invention. Among these are, difficulty of attachment to the engine, leaky construction, the production of the spark in a chamber or restricted pocket or portion of the igniter whereby the flame propagation is seriously hampered, arrangements whereby soot and carbon collect on the working parts especially the contacts between the electrodes thereby opening the circuit, and arrangements whereby the circuit is from one electrode to the engine piston wherein the spark is always produced "late". These objections are overcome in my device, as hereinafter described and claimed.

The invention will be clearly understood by reference to the annexed drawings, in which the same figures refer to the same parts whenever they are shown.

Figure 1 is a view partly in section of my igniter. Fig. 2, a view of a modified form showing the advance and retard mechanism. Fig. 3 is an external view of an engine cylinder showing how the advance and retard "timing" is accomplished by open visual indication. Fig. 4 shows a cylinder end view of the igniter, Fig. 2, Fig. 5, shows the cylinder end of the igniter shown in Fig. 1.

1 represents the wall of an engine cylinder, 2 the engine piston.

3 is the usual cylinder head, which for the sake of illustration is shown separate from the cylinder wall, although it is obvious that the same may be cast integral therewith.

In a suitable aperture in 3 is located the threaded body 4 of the igniter as shown in Fig. 1. It is obvious however that this body may be constructed in the form shown in Fig. 2 and bolted or otherwise attached to the cylinder. The arrangement shown in Fig. 1 is advantageous as one igniter body may be adapted to engines having cylinder heads or walls of various thickness by providing a collar 5 of the proper length for a given engine, and clamping this collar between the body 4 and the cylinder head 3, by the means of a clamp nut 6.

The body 4 Fig. 1 is drilled as indicated at 7 to receive an electrode 8 the same being insulated from 4 by means of any suitable material such as mica placed as indicated at 9 and 10. The cylinder end of 8 is shaped as shown at 11 and is provided with a suitable contact point, 12, which may be riveted thereto.

The outer end of 8 is provided with a suitable clamping means 13, for attaching the conductor 14 leading to a suitable ignition device such as a magneto, the return circuit being completed via the engine frame and igniter body.

The moving electrodes consist of the plunger 15, having an offset portion 16, carrying a suitable contact 17. The contacts 17 and 12 are held in normal contact by means of the spring 18 on 15, arranged to exert its tension outwardly, toward the piston, as shown.

The end 19 of the plunger projects outwardly beyond the end of the body 4, but may be normally covered with a projecting cap 20. To ascertain at what time in the

piston cycle the points 12 and 17 separate, it is only necessary to remove the cap 20 and observe the position of 19.

To keep the plunger 15 from rotating and thereby getting the contact points 12 and 17 out of line, the offset portion 16 rides the small pin 21, whereby the points are held in line.

In operation, the contact points 12 and 17 are normally closed, the piston 2 not being in engagement with the end of 15; but upon the piston occupying the position shown by dotted line 22, representing the dead center, or slightly before this point is reached, the points are opened by piston 2 pushing 15 outwardly. The circuit thus being broken, a spark takes place within the compressed mixture in the cylinder, which is ignited in the usual manner.

It will be seen from the foregoing description that the igniter as a whole may be adjusted to suit cylinder heads or walls of various thickness: that the igniter may be removed from the engine without disturbing any of the operative parts of the igniter and particularly those that should not be disturbed, such for instance as insulation 9 and 10, and that the outer end 19 of plunger 15 may be readily observed by removing the cap 20, thereby enabling the timing of the engine to be readily checked by open visual indication. It is also observed that the construction shown results in gas tight joints without the use of packing between the cylinder and igniter proper, or the use of packing in parts of the igniter. The insulation 9 and 10 around the electrode 8 is usually mica, and is of solid construction and cannot be considered in the nature of packing.

While the igniter shown in Fig. 1 is particularly adapted to engines in which the timing of the ignition is fixed, there are engines in which it is desirable to advance and retard the timing of the spark in its relation to the piston, and for such engines, I provide the arrangement shown in Fig. 2. The electrode 8 is supported in a sleeve 23 which is insulated by means of any suitable material, at 24 and 25. The electrode 8 is movable within the tube 23 in the following manner: 26 denotes an insulating bushing, screwed or otherwise attached to the threaded end of 8. The annular ring 27 in 26 is engaged by the downwardly projecting portion of the nut 28, carried on a threaded stem 29, said stem being revolvable by means of handle 33. 29 and 33 are both carried on a suitable stud 31 supported by the boss 32 in the igniter body 4. By rotating the handle 33, the electrode 8 may be moved toward or away from the piston, and the plunger 15 will partake of such movement, being moved against spring 18. 65 This movement is accomplished by the nut

28 running back and forth on the threaded stem 29 as the latter is rotated on its supporting stud 31. This causes the end 34 of plunger 15 to be advanced nearer to or farther away from the piston 2, and therefore the points 17 and 12 are opened at a time in relation to the piston depending upon the relative position of handle 33. The indicator 30 rigidly attached to 31 may be provided, as shown in Fig. 3, whereby the relative advance or retard in degrees of the ignition firing point in relation to the position of the piston may be determined by the relation of the graduated portion of the handle 33 thereto, as shown.

The igniter body 4 is attached to the engine cylinder in Fig. 2 in any suitable manner as by bolts and nuts indicated at 35 and 36 and it will be apparent that by removing these nuts the entire igniter may be removed from the engine without changing the relative position of the various parts, or changing the setting of the timing. And while I have shown the igniter mounted on the end of a cylinder, it is obvious that same may be mounted on the side of the cylinder, as well, and operated by means of a suitable bell crank arrangement.

There are other obvious modifications, all of which are within the scope of my invention.

It will be noticed that the contacts 12 and 17 are openly positioned in the combustion space within the cylinder, and that these are of the usual removable or rivet type. There are no pockets or inclosed places surrounding these points, in which soot and carbon can collect, a serious defect in some forms of igniters.

Having thus described my invention, I claim:

1. An igniter comprising a single stem electrode having a freely projecting contact point, insulation about said electrode, a second electrode carrying a freely projecting contact and having an extended portion adapted to directly engage an engine piston, tension means for holding the contacts of said electrode normally in contact, and a body member upon which all of the foregoing parts are mounted to form a removable unit, said body member inclosing said tension means and adapted to be rigidly secured to an engine whereby said contact points project freely into the combustion chamber thereof, substantially as described.

2. An igniter comprising a fixed body adapted to be secured to an engine cylinder, a single stem stationary electrode carried by said body insulated therefrom, and having a contact point, a movable electrode stem carried by said body in electrical contact therewith and adapted to directly engage an engine piston, and tension means for holding said electrodes in contact, said ten-

- sion means surrounding said movable electrode where it passes through said body, substantially as described.
3. An igniter comprising an externally threaded one-piece body, a longitudinal aperture therein, an insulated solid electrode immovably supported in said aperture, a second longitudinal aperture in said body, a movable electrode supported in said last aperture, and in contact with said body, a spring surrounding a portion of said movable electrode, said spring being inclosed by said body, a cylinder wall adapted to receive a portion of said threaded body, and means surrounding a portion of said igniter body and coöperating with said cylinder wall, whereby said body may be locked in position.
4. An igniter comprising a body, an electrode in said body, insulated therefrom and having a contact point adapted to project beyond said body and freely into an engine cylinder, a second electrode having an extension adapted to engage an engine piston, and means for moving one of said electrodes in relation to the piston operated electrode, substantially as described.
5. In combination with an internal combustion engine, an igniter comprising a body rigidly secured to said engine, a movable electrode having a contact point carried in said body and adapted to be operated by the piston of said engine, a second electrode coöperating with the contact point on said first electrode, means for adjusting said electrodes in relation to said piston, and means for preventing axial rotation of said electrodes.
6. In combination with an internal combustion engine, an igniter comprising a body rigidly secured to said engine, a movable electrode having a contact point carried in said body, and adapted to be operated by the piston of said engine, a second electrode having a contact point coöperating with said first contact point, means for adjusting said electrodes in relation to said piston, said means including the stem of one of said electrodes, and means for preventing axial rotation of said second electrode.
7. In combination with an internal combustion engine, an igniter comprising a body rigidly secured to said engine, a movable electrode having a contact point carried in said body and adapted to be operated by the piston of said engine, a second electrode having a contact point coöperating with said first contact point, means for adjusting said electrodes in relation to said piston, said means including an outwardly projecting portion on one of said electrodes adapted to be engaged by adjusting mechanism carried on said body and forming a unit therewith, and means for preventing axial rotation of one of said electrodes, substantially as described.
8. In combination with an internal combustion engine, an igniter comprising a body rigidly secured to said engine, a movable electrode carried in said body adapted to be operated by the piston of said engine, and having a contact point, a second electrode coöperating with said first contact point, adjusting means carried on said body whereby said electrodes may be moved nearer to or farther away from said piston, the travel of said electrodes being in plane with the movement of said piston, and means for preventing axial rotation of one of said electrodes.
9. In combination with an internal combustion engine, an igniter body adapted to be secured thereto, movable electrodes carried by said body, and having freely projecting contact points, means for adjusting said electrodes in relation to the piston of said engine, and means for preventing one of said electrodes from turning in its support.
10. In combination with an internal combustion engine, an igniter body adapted to be secured thereto, movable electrodes carried by said body and having freely projecting contact points, means for adjusting said electrodes in relation to the engine piston, means located external said body for determining the position of said electrodes relative to said piston, and means to prevent one of said electrodes from rotating, substantially as described.
11. In combination with an internal combustion engine, an igniter body adapted to be secured thereto, movable electrodes carried by said body and having freely projecting contact points, means for adjusting said electrodes in relation to the piston of said engine whereby the timing of the ignition may be varied during the normal running thereof, said means including mechanism mounted on said body and removable from the engine therewith as a unit, and means preventing the rotation of said electrodes.
12. In combination with an internal combustion engine, an igniter body adapted to be secured thereto, movable electrodes carried by said body, and having freely projecting contact points, means for adjusting said electrodes in relation to the piston of said engine, including a graduated indicator, and means preventing the rotation of said electrodes.
13. In combination with an internal combustion engine, an igniter body adapted to be secured thereto, movable electrodes carried by said body, and having freely projecting contact points normally in contact, means for adjusting both of said electrodes in relation to the piston of said engine, in-

cluding a graduated indicator, an extension on one of said electrodes projecting outside said body and forming a second indicator whereby the position of said electrode may be determined.

14. In combination with an internal combustion engine, an igniter body adapted to be secured thereto, movable electrodes carried by said body, means for adjusting said electrodes in relation to the piston of said engine, including a graduated indicator, an extension on one of said electrodes projecting outside of said body and forming an indicator, and a cap normally covering said extension.

15. In combination with an electric igniter of the piston operated type, means for varying the position of both the igniter electrodes, indicating means for determining the position of said electrodes, in relation to said piston, and separate indicating means for determining the position of one of said electrodes.

16. An electric igniter comprising a unitary structure carrying movable electrodes having contact points, tension means for holding said electrodes in normal engagement, means for varying the position of said electrodes in relation to the other parts, means for indicating the relative position of said electrodes, and separate indicating means for determining the position of one of said electrodes.

17. An electric igniter comprising a body, make and break igniter mechanism carried thereby, and having contacts projecting freely into the combustion space of said engine, a circuit terminal, means for varying the timing of said mechanism, and means for preventing rotation of the electrodes, all of the foregoing being assembled as a unit, and adapted to be removed or replaced without disassembly, substantially as described.

18. In combination with an internal combustion engine, an igniter comprising a body, an electrode movably positioned therein but insulated therefrom, a second electrode adapted to coöperate with said first electrode, and adapted to be engaged by the engine piston, means external said body for adjusting said electrodes in relation to the engine piston, said means including the stem of said first mentioned electrode, and means for preventing rotation of said electrodes, substantially as described.

19. In combination with an internal combustion engine, an igniter comprising a body, electrodes positioned in said body and having their extremities equipped with contact points within the engine cylinder to

form a make and break igniter operated by the piston of said engine, means for adjusting the timing of contact between the engine piston and said make and break mechanism, said means including the stem of one of said electrodes, and means for preventing rotation of said electrodes.

20. An igniter comprising a body carrying a pair of electrode stems, contacts carried by said stems, an extension on one of said stems adapted to engage an engine piston, and means for maintaining the axial alinement of said contacts and preventing the rotation of said stems, substantially as described.

21. An igniter comprising a casting having an apertured body portion, a tapered stem in said aperture, insulation between said stem and body, an extension on said stem projecting outside said body and forming a terminal for said stem, a contact secured to the inner end of said stem, means for clamping said stem in said body whereby the stem is rigidly secured therein, a second aperture in said body, a stem in said last aperture, a contact member on said last stem adapted to engage the contact member on said first mentioned stem, means for holding said contacts normally in contact with each other, means for preserving the alinement of said contacts, and means for opening said contacts, substantially as described.

22. In combination with an internal combustion engine, an igniter comprising a one piece body rigidly secured to said engine, a movable electrode carried in said body and adapted to be operated by the piston of said engine, and a second electrode coöperating with said first electrode and insulated from said body and self-locking means for adjusting said last mentioned electrode in relation to said piston.

23. In combination with an internal combustion engine, an igniter comprising a one piece body rigidly secured to said engine, a movable electrode carried in said body and adapted to be operated by the piston of said engine, a second electrode coöperating with said first electrode and insulated from said body, self-locking means for adjusting said last mentioned electrode in relation to said piston, said means including an outwardly projecting extension on one of said electrodes, a traveling nut engaging said outwardly projecting portion of said electrode, and means for operating said traveling nut.

In testimony whereof I hereunto affix my signature.

WILLIAM GRUNOW, JR.
